Patented Dec. 30, 1958

184,194

GARAGE

Carl W. Pirscher and Samuel P. Havis, Oak Park, Mich.,
assignors to Fairway Construction Company, Detroit,
Mich., a corporation of Michigan

Application October 7, 1957, Serial No. 47,990

Term of patent 14 years

(Cl. D13—1)

FIG. 1.

FIG. 2.

FIG. 3.

FIG. 4.

The rear of the garage not shown on the drawing is substantially plain.

We claim:

The ornamental design for a garage, substantially as shown and described.
